TAMPER-PROOF CONTAINER CLOSURE

Jerome M. Feldman, Great Neck, N.Y., assignor to Hi-Tech Industries, Incorporated, Jamaica, N.Y.

Filed Sept. 14, 1972, Ser. No. 289,070

Term of patent 14 years

Int. Cl. D9—07

U.S. Cl. D9—287

FIG. 1

FIG. 2

FIG. 3

FIG. 5

FIG. 4

FIG. 1 is a perspective view of a tamper-proof container closure, showing my new design;

FIG. 2 is a top plan view;

FIG. 3 is a bottom plan view;

FIG. 4 is a front elevational view; and

FIG. 5 is a top plan view of a tamper-proof container closure showing a modified form of my new design wherein the triangular cut adjacent the attached end of the pull tab is omitted.

I claim:

The ornamental design for a tamper-proof container closure, as shown and described.
